US0D1012832S

(12) **United States Design Patent** (10) **Patent No.:** **US D1,012,832 S**
(45) **Date of Patent:** **** Jan. 30, 2024**

(54) **SOLAR PANEL**

- (71) Applicant: **MAXEON SOLAR PTE. LTD.**,
Marina Bay Financial Centre (SG)
- (72) Inventors: **Ratson Morad**, Palo Alto, CA (US);
Gilad Almogy, Palo Alto, CA (US);
Itai Suez, Santa Cruz, CA (US); **Jean**
Hummel, San Carlos, CA (US);
Nathan Beckett, Oakland, CA (US)
- (73) Assignee: **MAXEON SOLAR PTE. LTD.**,
Marina Bay financial Center (SG)
- (**) Term: **15 Years**
- (21) Appl. No.: **29/691,305**
- (22) Filed: **May 15, 2019**

- (60) Division of application No. 29/617,566, filed on Sep. 14, 2017, which is a continuation of application No. 15/359,326, filed on Nov. 22, 2016, now Pat. No. 10,090,430, which is a continuation of application No. PCT/US2015/032472, filed on May 26, 2015, which is a continuation-in-part of application No. 14/530,405, filed on Oct. 31, 2014, now Pat. No. 9,780,253, and a continuation-in-part of application No. 14/532,293, filed on Nov. 4, 2014, now abandoned, and a continuation-in-part of application No. 14/536,486, filed on Nov. 7, 2014, now abandoned, and a continuation-in-part of application No. 14/539,546, filed on Nov. 12, 2014, now abandoned, and a continuation-in-part of application No. 14/543,580, filed on Nov. 17, 2014, now Pat. No. 9,882,077, and a continuation-in-part of application No. 14/548,081, filed on Nov. 19, 2014, now abandoned, and a continuation-in-part of application No. 14/550,676, filed on Nov. 21, 2014, now abandoned, and a continuation-in-part of application No. 14/552,761, filed on Nov. 25, 2014, now abandoned, and a continuation-in-part of application No. 14/560,577, filed on Dec. 4, 2014, now Pat. No.

9,876,132, and a continuation-in-part of application No. 14/566,278, filed on Dec. 10, 2014, now abandoned, and a continuation-in-part of application No. 14/565,820, filed on Dec. 10, 2014, now abandoned, and a continuation-in-part of application No. 14/572,206, filed on Dec. 16, 2014, now Pat. No. 9,401,451, and a continuation-in-part of application No. 14/577,593, filed on Dec. 19, 2014, now Pat. No. 9,356,184, and a continuation-in-part of application No. 14/586,025, filed on Dec. 30, 2014, now abandoned, and a continuation-in-part of application No. 14/585,917, filed on Dec. 30, 2014, now abandoned, and a continuation-in-part of application No. 14/594,439, filed on Jan. 12, 2015, now Pat. No. 9,397,252, and a continuation-in-part of application No. 14/605,695, filed on Jan. 26, 2015, now Pat. No. 9,484,484, and a continuation-in-part of application No. 14/674,983, filed on Mar. 31, 2015, now Pat. No. 9,947,820, and a continuation-in-part of application No. 29/506,415, filed on Oct. 15, 2014, now abandoned, and a continuation-in-part of application No. 29/506,755, filed on Oct. 20, 2014, now abandoned, and a continuation-in-part of application No. 29/508,323, filed on Nov. 5, 2014, now abandoned, and a continuation-in-part of application No. 29/509,586, filed on Nov. 19, 2014, now Pat. No. Des. 750,556, and a continuation-in-part of application No. 29/509,588, filed on Nov. 19, 2014, now Pat. No. Des. 767,484.

CLAIM

The ornamental design for a solar panel, as shown and described.

DESCRIPTION

FIG. 1 is a front, top, and right side perspective view of a first embodiment of a solar panel;

FIG. 2 is a front elevational view thereof, the rear elevational view forms no part of the claimed design;

FIG. 3 is a top plan view thereof, the bottom plan view being a mirror image of the top plan view shown;

FIG. 4 is a left side elevational view thereof, the right side elevational view being a mirror image of the left side elevational view shown;

FIG. 5 is an enlarged detail view thereof, taken along line 5-5 in FIG. 2;

FIG. 6 is a front, top, and right side perspective view of a second embodiment of a solar panel;

FIG. 7 is a front elevational view thereof, the rear elevational view forms no part of the claimed design;

FIG. 8 is a top plan view thereof, the bottom plan view being a mirror image of the top plan view shown;

FIG. 9 is a left side elevational view thereof, the right side elevational view being a mirror image of the left side elevational view shown;

FIG. 10 is an enlarged detail view thereof, taken along line 10-10 in FIG. 7;

FIG. 11 is a front, top, and right side perspective view of a third embodiment of a solar panel;

FIG. 12 is a front elevational view thereof, the rear elevational view forms no part of the claimed design;

FIG. 13 is a top plan view thereof, the bottom plan view being a mirror image of the top plan view shown;

FIG. 14 is a left side elevational view thereof, the right side elevational view being a mirror image of the left side elevational view shown; and,

FIG. 15 is an enlarged detail view thereof, taken along line 15-15 in FIG. 12.

The broken lines in the drawings illustrate subject matter that forms no part of the claimed design.
